UNITED STATES PATENT OFFICE.

JESSE BARBER, OF WYOMING, KENTUCKY, ASSIGNOR OF ONE-HALF TO
T. J. JONES, OF SAME PLACE.

BUGGY-WRENCH.

SPECIFICATION forming part of Letters Patent No. 600,605, dated March 15, 1898.

Application filed June 12, 1897. Serial No. 640,501. (No model.)

To all whom it may concern:

Be it known that I, JESSE BARBER, of Wyoming, in the county of Bath and State of Kentucky, have invented certain new and useful 5 Improvements in Buggy-Wrenches; and I do hereby declare the following to be a full, clear, and exact description of the invention, such as will enable others skilled in the art to which it appertains to make and use the same.

10 My invention relates to buggy-wrenches; and its object is to provide an improved form of buggy-wrench in which the wheel and the axle-nut will be taken off together.

15 My invention consists of certain novel features of construction and combinations of parts hereinafter fully described and claimed.

In the accompanying drawings, Figure 1 is a perspective view of my invention, taken from the front thereof. Fig. 2 is a bottom 20 plan view.

The numeral 1 indicates the body of my device, which is provided with a pair of handles 2. A longitudinal opening 3, the central portion of which has parallel sides, is formed in 25 said body portion. A socket-wrench 4 is held securely on the body portion of my device at about the middle point thereof. Sliding blocks 5 are held to move in the parallel-sided slot before mentioned. Thumb-latches 30 6 are formed upon said sliding blocks, being adapted to receive a wheel-hub between them. A spring 8 attached to said blocks normally holds the same in a closed position.

When it is desired to operate my device, it is simply necessary to spread the sliding 35 blocks by means of the thumb-latches, place the whole device over a wheel, and use as an ordinary wrench. The spring will hold the clamps upon the sliding blocks tightly against the wheel-hub, so that when the nut is rotated by the socket-wrench both the nut and the wheel will be removed together.

I thus provide a simple and efficient means for accomplishing the above-described object, which may be readily manufactured at low 45 cost.

Having thus described my invention, what I claim as new, and desire to secure by Letters Patent, is—

1. In a buggy-wrench, the combination with 50 a handle, of a socket-wrench formed thereon, clamps held to slide upon said handle, and a spring normally urging said clamps together.
2. In a buggy-wrench, the combination with 55 a handle having a longitudinal slot therein, of a socket-wrench formed upon said handle, clamps held to slide in said slot, thumb-latches formed upon said clamps and a spring normally urging said clamps together.

In testimony whereof I have signed this 60 specification in the presence of two subscribing witnesses.

JESSE BARBER.
